CLAIM

The ornamental design for a valve for a linear electric submersible pump, as shown and described.

DESCRIPTION

FIG. 1 is a perspective view of a valve for a linear electric submersible pump;

FIG. 2 is a top perspective exploded view of the valve for the linear electric submersible pump of FIG. 1; and,

FIG. 3 is an underside perspective exploded view of the valve for the linear electric submersible pump of FIG. 1.
